FRANK J. EVANS AND HERMAN C. HANSEN, OF MINNEAPOLIS, MINNESOTA, AS
SIGNORS TO WILLIAM L. SIX, OF KANSAS CITY, MISSOURI.

OIL BURNER.

Application filed December 26, 1922. Serial No. 608,872.

This invention relates to a liquid fuel burner or to an oil burner. Such burners are now generally being installed, both in stoves designed for cooking purposes and in heating plants for dwellings and other buildings. Such burners are very desirable, owing to the elimination of the use of coal with the attending difficulty of shoveling the same and removing the ashes from the furnaces. With the oil burners, a fuel plant is easily handled and all dust, dirt and ashes are practically eliminated. One difficulty with certain types of burners now in use is that when the same are regulated so as to burn low, there is a faulty generation of the gas necessary to the operation of the burner.

It is an object of this invention, therefore, to provide such a device as above referred to which comprises a main burner and an auxiliary generating burner.

It is a further object of the invention to properly dispose said burners and to provide the same with a common regulating means adapted to be operated by a thermostat or other temperature controlled device.

These and other objects and advantages of the invention will fully appear from the following description made in connection with the accompanying drawings in which like reference characters refer to the same parts throughout the different views and in which,

Fig. 1 is a view in front elevation of the burner, certain portions thereof being shown in section;

Fig. 2 is a vertical section taken on the line 2—2 of Fig. 1, as indicated by the arrows; and

Fig. 3 is a vertical section through one of the regulating valves of the burner.

Referring to the drawings, an inlet pipe 1 is shown which, in the type of burner disclosed, will be connected to a liquid fuel or oil supply tank and through which the oil will, preferably be fed by gravity. This conduit 1 connects with the casing 2 at the bottom of said casing and substantially at the transverse center thereof. Casing 2, as shown, has a chamber at the bottom portion and is also provided with upwardly extending branches 3 which are connected at their upper ends by pipes 4 comprising elbows 5 to a T member 6 from which a conduit 7 leads laterally and downwardly, said conduit

having therein the elbow 8. The lower end of the conduit 7 is provided with an elbow 9 from which a horizontal pipe 10 leads having connected thereto a main spraying head or burner 11 and an auxiliary spraying head 12. Said burners or heads have screwed into their upper ends, plugs 13 provided at their upper ends with small central passages 14. The plugs 13 are provided with conical passages below the passages 14 forming the valve seat for needle valves 15, which valves are in the form of rods and extend downwardly from said burners through pipes 16 and 17.

The casing 2 is provided immediately above its lower portion with an open top pan 18 extending at each side of the branches 3 and between the same. The pipes 16 and 17 extend through this pan and, as shown in Fig. 2, are connected to the burners of heads 11 and 12. The head 11 is thus substantially in the form of a standard T and the burner or head 12 is in the form of a standard cross T having a short section of pipe screwed into this open end which receives the plug 13. A pipe or conduit 19 connects with the pan 18, being threaded into a boss on the lower side thereof. The conduits 16 and 17 are connected adjacent their lower portions with a strap member forming a support for a downwardly extending bracket 20, to the lower end of which is pivoted a lever 21. This lever is provided with a slot 23 adjacent one end through which, and the lower end of one of the rods 15 passes a pivot connecting member 22 shown as a split key. The lever is provided with another slot 24 disposed substantially the same distance from its pivot as the slot 23 and a pivot connecting member 25 also illustrated as a split key extends through this slot and the lower end of the other rod 15. The other end of the lever 21 extends some distance to the side of the last mentioned rod 15 and is operated and adapted to be connected to an operating member which, in turn, may be connected to a thermostat or other temperature controlled means disposed in the building or chamber adapted to be heated by the burner.

The conduit 1 is provided with a regulating valve 26 having the usual operating hand wheel and is further provided with an emptying or discharge valve 27 disposed above the valve 26, which valve 27 is also provided with the usual hand wheel. A

2

deflecting and heating member 28 extends between the upper ends of the branches 3 of the casing 2 and is of sufficient width to extend over each of the burners 11 and 12.

5 In operation, the oil or other liquid fuel will flow by gravity through the pipe 1 and will substantially fill the casing 2, branches 3 and the pipes 4, 7 and 10. A wick or pad 29 of some suitable material is placed in the pan 18 and when the burner is first started the oil will be allowed to flow through the heads 11 and 12 and the aperture 14 into the pan 18 to saturate the member 29. The same can then be ignited and the flame caused thereby will extend upwardly about the portions 3 of the casing and the members 28, and these members, together with the pipes 4 and 7, will be heated. During this heating the valve 26 will be closed. When the oil run onto the pan 18 is thus burned and consumed, the valve 26 will be again opened. When the members 3, 4 and 7 are heated the oil therein is heated and placed under some pressure. The oil tends to vaporize and will issue in a fine jet or spray through the openings 14. The spraying will be directed upwardly against the deflecting member 28 which is heated and the spray of fuel will here be completely vaporized. This vaporized fuel will be mixed with the surrounding air and ignited and the flame will thus spread out around from under the member 28 and against the walls of the casing branches 3 and the pipes 4 and 7. When the burner is burning at large capacity or with a large flame, the rod 15 of the main burner 11 will be depressed so that the aperture 14 in the head or burner 11 will be open to a great extent. The other rod 15 will be elevated so that the aperture in the burner 12 will be largely closed. When the main burner is therefore burning at a large part of its capacity the burner 12 will be largely shut off. When the chamber or plate to be heated is heated to a sufficient degree the lever 21 will be operated to shut off the burner 11 and reduce the flame thereof and at the same time the auxiliary burner 12 will be turned on the same degree. It will be understood that the burner 12 is of smaller capacity than the burner 11 and, as described, is disposed closer to the spreading plate 28. When the burner 11 is thus turned down, the burner 12 will insure that there is sufficient heat produced and transmitted to the members 3 and 28 to give perfect action and generation of the fuel. The burner can thus be automatically regulated without any danger of surplus oil issuing through the spraying heads or burners thereof and thus causing trouble. If for any reason any oil should flow through the burners and be ignited, the same will pass off through the pipe 19 and be led to some suitable recep-

tacle. The valve 27 is provided in case it is desired at any time to drain the burner for cleaning, inspection or other purpose. At this time, the valve 26 will be closed and the oil which is contained in the members 2, 3 and 4 will be drained out of said valve.

From the above description it is seen that applicants have made a great improvement upon a device of the type described. By providing the auxiliary burner the main burner can be regulated without danger of reducing the generating heat below the desired point. The regulation of the main and auxiliary burners can be positively made by automatic means. The burner is simple in construction and can be made largely from standard parts. If desired, the member 28 may be made of fire brick or any suitable refractory material capable of holding considerable heat. When the burner is once assembled the same operates with no trouble and there is no objectionable smoking or accumulation of soot or carbon about any of the parts of the same. The invention has been amply demonstrated in actual practice and found to be very successful.

It will, of course, be understood, that various changes may be made in the form, details, arrangement, and proportions of the parts without departing from the scope of applicants' invention, which, generally stated, consists in the matter shown and described and set forth in the appended claims.

What is claimed is:

1. A liquid fuel burner having in combination, a substantially horizontal pan, spaced pipes extending vertically therethrough, a burner secured to the upper end of one of said pipes, an auxiliary burner of small capacity secured to the upper end of the other of said pipes and extending above said first mentioned burner, regulating valves in said burners, and means disposed below said pan connected to said valves for moving the same so that when the valve of the first mentioned burner is open the valve of the last mentioned burner is partially closed, and vice versa, and a substantially horizontal deflecting plate disposed above both burners.

2. A liquid fuel burner having in combination, a substantially horizontal pan, spaced pipes extending vertically therethrough, a burner secured to the upper end of one of said pipes, an auxiliary burner of smaller capacity secured to the upper end of the other of said pipes and extending above said first mentioned burner, regulating valves for said burners, plungers extending downwardly therefrom through said pipes, a bracket secured to said pipes below said pan, a lever pivoted to said bracket and respectively connected to said plungers at each side of its fulcrum, one end of said lever extending laterally and

adapted to be connected to a regulating means.

3. A liquid fuel burner comprising an inlet conduit, a chamber into the bottom of which said conduit delivers, said chamber having upwardly extending branches at the sides thereof, said branches having a connection at their upper ends, a conduit leading downwardly from said connection, a main burner and an auxiliary burner connected with said last mentioned conduit and disposed substantially between the said branches, said auxiliary burner being higher than said main burner, and a horizontal spreading device disposed above and over both burners.

4. A liquid fuel burner comprising an inlet conduit, a chamber into the bottom of which said conduit delivers, said chamber having upwardly extending branches at the sides thereof, said branches having a connection at their upper ends, a pipe leading downwardly from said connection at one side thereof and between said branches, a vertically disposed cross T having one horizontal arm secured to the lower end of said pipe, a reduced burner head secured in the upper arm of said T, a conduit extending downwardly from the lower arm of said T, a pipe extending from the horizontal arm of said T opposite said pipe, a vertically disposed T having its intermediate arm secured to said latter pipe, a conduit

extending downwardly from the lower end of said latter T, a burner secured in the upper end of said latter T and disposed at a lower height than said first mentioned burner, a pan beneath said T through which said conduits extend adapted to form a priming pan, valves in said burners disposed therein and in said T's, plungers extending downwardly from said valves through said conduits, and means carried by said conduits beneath said pan for simultaneously adjusting said valves in opposite directions.

5. A liquid fuel burner comprising, an inlet fuel conduit, a casing to which the same is connected, an upstanding main burner and an upstanding auxiliary burner connected to said casing, said auxiliary burner being of less capacity than and disposed at a greater height than said main burner, regulating valves for said burners, regulating means for said valves extending downwardly therefrom, a lever fulcrumed between said regulating means and connected thereto at each side of said fulcrum, said lever being adapted to be connected to a temperature control device whereby said burners will be oppositely regulated.

In testimony whereof we affix our signatures.
